(57) **CLAIM**

The ornamental design for a wall and roof covering panel, as shown and described.

DESCRIPTION

FIG. 1 is a front perspective view of a wall and roof covering panel;

FIG. 2 is a rear perspective view of the wall and roof covering panel shown in FIG. 1;

FIG. 3 is a front elevation view of the wall and roof covering panel shown in FIG. 1;

FIG. 4 is a rear elevation view of the wall and roof covering panel shown in FIG. 1;

FIG. 5 is a top plan view of the wall and roof covering panel shown in FIG. 1;

FIG. 6 is a bottom plan view of the wall and roof covering panel shown in FIG. 1;

FIG. 7 is a left-side elevation view of the wall and roof covering panel shown in FIG. 1; and,

FIG. 8 is a right-side elevation view of the wall and roof covering panel shown in FIG. 1.

The wall and roof covering panel discloses symbolic breaks along the center of its length and width, shown as longer

(Continued)

dashed-dot broken lines. The appearance of any portion of the article between the break lines forms no part of the claimed design.

1 Claim, 8 Drawing Sheets
